Primary Examiner—Doris V. Coles**Assistant Examiner**—Mimosa De(74) **Attorney, Agent, or Firm**—Boyle Fredrickson Newholm Stein & Gratz S.C.(57) **CLAIM**

The ornamental design for a vehicle seat, as shown and described.

DESCRIPTION

FIG. 1 is a front perspective view of a vehicle seat in accordance with the present invention;

FIG. 2 is a front elevational view of the vehicle seat;

FIG. 3 is a right side elevational view of the vehicle seat;

FIG. 4 is a back elevational view of the vehicle seat;

FIG. 5 is a top plan view of the vehicle seat; and,

FIG. 6 is a bottom plan view of the vehicle seat.

The left side elevation view comprises a mirror image of the right side elevational view depicted in FIG. 3.
